AMÉDÉE LETHIECQ, OF NEVILLE, SASKATCHEWAN, CANADA

GRAIN STOOKER

Application filed June 19, 1928. Serial No. 286,694.

The present invention relates to a grain stooker and has for its object to provide a device for stooking sheaves of grain as they come from the binder. The device takes the place of the bundle carrier on the ordinary binder.

With the above and numerous other detailed objects as will appear as the description proceeds, the invention resides in certain novel features of construction, and in the combination and arrangement of parts as will be hereinafter more fully described and claimed.

In the drawings:

15 Figure 1 is a side elevation of the device showing the basket ready to receive a sheaf from the binder.

Figure 2 is a similar view, showing the basket in its releasing position.

20 Figure 3 is a vertical transverse section taken substantially on the line 3—3 of Figure 1, looking rearwardly.

Figure 4 is a perspective view of the device.

25 Figure 5 is a side elevation opposite to that shown in Figure 1.

Figure 6 is a vertical longitudinal section showing the basket in a releasing position.

30 Figure 7 is an enlarged detail sectional view taken substantially on the line 7—7 of Figure 1.

Figure 8 is an enlarged detail section, taken substantially on the line 8—8 of Figure 1, and

35 Figure 9 is a perspective view of the ejector.

Referring to the drawings in detail, it will be seen that the letter F denotes the main frame of the device, which is of U-shaped formation, to include a curved bight portion 5 at the front, and rearwardly extending sides 6 and 7. The side 6 is the off side, in respect to the binder and is supported by a wheel 8, journaled intermediate the ends thereof by a stub axle 9 or in any other suitable manner. The near side 7, that is the side adjacent the binder, is supported, by suitable means (not shown), by the frame of the binder.

50 An auxiliary frame is designated gener-

ally by the letter A and is substantially U-shaped in formation to provide a curved bight portion 11 and sides 12. Arms 14 and 15 project from the extremities of the sides 12, obliquely thereto. The arm 14 is provided with a longitudinally extending slot 16. A crank 17 is rockably mounted on the side 7, by means of a bracket 18 and has an end slidable in the slot 16. Obviously, by tripping the crank 17, the frame A may be 55 rocked to be disposed either as shown in Figure 1, or to the position as shown in Figures 2, 4, and 6. In this connection, it is to be noted that the arms 14 and 15 are pivoted to the sides 6 and 7 as at 19.

60 L-shaped brackets B include legs 20, secured to intermediate portions of arms 14 and 15 and legs 21, secured to intermediate portions of sides 12. The legs 21 are provided with turned over longitudinally extending flanges 22, on the inner sides thereof. A basket 23 has open ends and open sides and is rockably mounted between the apices of the brackets B by means of a rod 24, extending thereabout transversely and having extremities journaled in the apices, one of said extremities journaled in the crank 25, having an end 26, extending through an arcuate slot 27, in an arm 28, pivoted to the side 7 by means of a bracket 29 and urged forwardly by a spring 20, anchored to an intermediate portion of the arm 28 and to a forward portion of the side 7 by a suitable element 31. An arcuate head piece 32 has its ends rockably mounted between sides 12 immediately adjacent their junctures with the bight portions 11 by means of a rod 33. A cross bar 34 extends between the extremities of the head 32, and has offset ends pierced by the rods 33. A plurality of tines 35, extend from the head 32, through the cross bar 34. A spring 36 is anchored to one side 12 and to the cross bar 34. A latch 37 is pivotally mounted as at 38, to the bight portion 11 and has a spring 39 engaged therewith and engaged with the cross bar 34, as at 40 to normally hold the latch engaged over the upper edge of the head 32, so as to normally hold said head in the bight 11.

95 This latch, however is provided with a 100

curved arm 41 to engage over the bight 5 to release the latch so as to allow the head and the tines to swing downwardly and rearwardly for dumping a sheaf as will be more apparent as the description proceeds. It will be seen that the spring 36 is so anchored to the cross bar 34, at the bottom edge thereof as indicated at 44, that the tines will be normally disposed in an elevated position as at Figure 6, except when the weight of a sheaf thereon will bear the rear extremities of the tines downwardly so that the sheaf may slip off onto the ground, and as soon as the sheaf has slipped off onto the ground, the tines will elevate to the position shown in Figure 6, ready for the latch 37 to catch over the head 32, when the auxiliary frame is raised to the position shown in Figure 5. An arm 45 is pivotally mounted on the forward portion of the side 6 by means of a bracket 46 and inclines upwardly and rearwardly and has its extremity longitudinally slotted as indicated at 47. A curved ejector rod 48 has portions journaled through intermediate portions of the sides 12 and one end thereof is extended as at 48' and has an extremity offset to extend through the slot 47, and an element 49 thereon is engaged with the spring 50 anchored on an intermediate portion of the arm 45 adjacent its pivoted end.

When the parts are in their normal position as shown in Figures 1 and 5, it will be seen that the basket has one end closed by the tines 35 and the open side is disposed upwardly and the portions of the edges of the basket are received between legs 21 and their flanges 22, as is best illustrated in Figure 8. A sheaf is delivered into the basket, so as to be lying on its side by the ordinary means of the binder, which delivers sheaves to the bundle carrier. The trip crank 17 is operated by a part of the binder (not shown) ordinarily used for tripping the bundle carrier and operated by the driver of the binder. When this trip crank 17 is operated, it swings the arm 14 upwardly and forwardly so as to thereby move the auxiliary frame A from an upwardly and forwardly inclined position to a substantially horizontal position inside of the main frame F and as the arm 41 strikes the bight 5, the latch 37 is released. The movement of the brackets B with the frame A cause the basket 26 to swing from the position shown in Figure 1 to a position shown in Figures 2, 4, and 6, since as the brackets move the axis of the basket in an arc, the crank 25 is controlled, by a pin 26, in the slot 27, so that the basket is inverted, and while being inverted, the basket forces the sheaf to an upright position against the ejector bar 48, which causes the spring 50 to be placed under tension while the basket is in an upright position, that is, in a position intermediate that shown

in Figures 1 and 2, and then as the basket completely inverts itself, the ejector moves the sheaf rearwardly on the tines 35 in an upright position and the tines 35 rock downwardly or rearwardly so as to allow the bundle or sheaf to slip off onto the ground in a standing position. Then the set crank is operated to return the parts, in a manner which will be quite apparent from the position shown in Figures 2, 4, and 6, to the position shown in Figures 1 and 5.

In describing the operation of this stoker, I have turned to its operation in connection with a single sheaf. However, in actual practice, it is to be understood that a plurality of sheaves will usually be placed in the basket before the same is dumped, and the ejector bar 48 will yield to the spring 50 to accommodate the number and size of the sheaf.

From the above detailed description it will be seen that I have devised a comparatively simple stoker which may be constructed in a strong and durable manner at a reasonable low cost, and yet be thoroughly efficient and reliable in use and operation. The structure has all of its parts arranged in an accessible manner, so that they may receive what little attention is necessary to the upkeep of the device.

The present embodiment of the invention has been disclosed in considerable detail for the purpose of exemplification, since in actual practice it attains the features of advantage enumerated as desirable in the statement of the invention and the above description.

It will be apparent that changes in the details of construction and in the combination and arrangement of parts may be resorted to, without departing from the spirit or scope of the invention as hereinafter claimed or sacrificing any of its advantages.

Having thus described my invention, what I claim as new is:

1. In combination, a main frame, adapted to have one side thereof supported on a binder, wheel means for supporting the other side of the main frame, an auxiliary frame, said arms pivoted to the main frame intermediate the ends thereof for rocking the auxiliary frame, the arm adjacent said one side provided with a slot, a trip crank rockable on the main frame and having a projection slideable in said slot, brackets rigidly secured to the intermediate ends of the arms and auxiliary frame, the arm adjacent said one side provided with a slot, a trip crank rockable on the main frame and having a projection slideable in said slot, brackets rigidly secured to the intermediate ends of the arms and auxiliary frame, a bracket having trunnions pivoted to the brackets, a bar pivoted at one end to the main frame and a slot on the other end, one of said trunnions termi-

nating in a laterally extending crank arm 5
slidable in said bar slot, a spring on the
main frame connected with said bar for
urging said bracket to a dumping position,
a head pivotally connected with the auxiliary
frame having tines mounted therein, a
latch pivotally connected to the main frame
and engageable with said head for locking
said head, an arm on the latch adapted to
10 abut the main frame in dumping position
to release the head, so that the sheaves will
slide therefrom.

2. In combination, a main frame adapted
15 to have one side thereof supported on a
binder, wheel means for supporting the
other side of the main frame, an auxiliary
frame, said arms pivoted to the main frame
intermediate the ends thereof for rocking
20 the auxiliary frame, the arm adjacent said
one side provided with a slot, a trip crank
rockable on the main frame and having a
projection slidable in said slot, brackets
rigidly secured to the intermediate ends of
25 the arms and auxiliary frame, the arm adja-
cent said one side provided with a slot, a
trip crank rockable on the main frame and
having a projection slidable in said slot,
brackets rigidly secured to the intermediate
30 ends of the arms and auxiliary frame, a
bracket having trunnions pivoted to the
brackets, a bar pivoted at one end to the main
frame and a slot on the other end, one of
said trunnions terminating in a laterally ex-
35 tendsing crank arm slidable in said bar slot,
a spring on the main frame connected with
said bar for urging said bracket to a dump-
ing position, a head pivotally connected with
the auxiliary frame having tines mounted
40 therein, a latch pivotally connected to the
main frame and engageable with said head
for locking said head, an arm on the latch
adapted to abut the main frame in dump-
ing position to release the head, so that the
45 sheaves will slide therefrom, a second bar
pivotally connected at one end to the main
frame and having a slot at the other end,
a curved ejector rod having one end pivoted
to the auxiliary frame, and at its other end
yieldingly pivoted in the slot of the second
50 bar to eject the formed shock in the dump-
ing position.

3. In combination, a main frame adapted
55 to have one side thereof supported on a
binder, wheel means for supporting the
other side of the main frame, an auxiliary
frame, said arms pivoted to the main frame
intermediate the ends thereof for rocking
60 the auxiliary frame, the arm adjacent said
one side provided with a slot, a trip crank
rockable on the main frame and having a
projection slidable in said slot, brackets
rigidly secured to the intermediate ends of
65 the arms and auxiliary frame, the arm adja-
cent said one side provided with a slot, a trip
crank rockable on the main frame and hav-

ing a projection slidable in said slot, brackets
rigidly secured to the intermediate ends
of the arms and auxiliary frame, a bracket
having trunnions pivoted to the brackets,
a bar pivoted at one end to the main
70 frame and a slot on the other end, one of
said trunnions terminating in a laterally ex-
tending crank arm slidable in said bar slot,
a spring on the main frame connected
with said bar for urging said bracket to a
75 dumping position, a head pivotally connected
with the auxiliary frame having tines
mounted therein, a latch pivotally connected
to the main frame and engageable with said
head for locking said head, an arm on the
80 latch adapted to abut the main frame in
dumping position to release the head, so that
the sheaves will slide therefrom, said brackets
being L-shaped and having the trunnions
mounted in the vertex thereof.

In testimony whereof I affix my signature.

AMÉDÉE LETHIECQ.
